UNITED STATES PATENT OFFICE.

ERICK P. BERGMAN, OF CONCORDIA, KANSAS.

WINDMILL.

No. 849,191.

Specification of Letters Patent.

Patented April 2, 1907.

Application filed April 17, 1906. Serial No. 312,099.

To all whom it may concern:

Be it known that I, ERICK P. BERGMAN, a citizen of the United States, residing at Concordia, in the county of Cloud and State of Kansas, have invented new and useful Improvements in Windmills, of which the following is a specification.

This invention appertains to improvements in windmills, and relates more particularly to the construction of the wind-wheel, the construction thereof being such as to provide means for supporting the blades and varying the angle thereof, such improvements embodying a hub that is rigidly attached to the driving-shaft, such hub having a solid front portion and a rearward-extending casing that covers the slide which is mounted on the shaft, the hub having attached thereto braces and supports for rings that carry the blades and the means for adjusting the blades, as will be hereinafter set forth.

In the accompanying drawings, forming a part of this specification, Figure 1 is a front elevation of a part of a wind-wheel made in accord with my invention. Fig. 2 is a vertical section, and Fig. 3 a rear elevation of a portion of the wheel.

The wheel A is mounted on a suitably-supported shaft B, that turns in bearings carried by the turn-table, such wheel including in its construction a hub B', that is made fast to the shaft B. The hub has a solid front portion, which is circumferentially recessed to provide flanges b and b', and from the outer circumference of the rear flange there extends a casing or conical cap B'', which overlies the sliding collar C, that is mounted on the shaft B to turn therewith. The sliding collar or sleeve C has a recess to receive the forked end of a slide-bar which is carried by the turn-table, the inner end thereof being attached to a bell-crank lever c, which is pivoted to a support that projects from the turn-table. The slide has a forwardly-projecting flange with openings for the reception of the ends of rods that are turned when the slide is moved, such rods moving a ring that is connected to the blades of the wheel to change the angle of the blades.

The rigid frame of the wheel includes a ring E, which is secured to the hub C by means of brace-rod e and e', the rods e being secured to the outer face of the flange b' and beneath the inner ends of the rods e', the inner ends of such rods e' being secured to the cap or casing B''. To the front flange b

of the hub there are secured brace-rod f, the outer ends of such rods being fastened to a ring F, and from the ring F to the flange at the rear edge of the casing B'' extend rods 60 f'. The rods e e' and f f' hold the rings E and F concentric, and such brace-rod are preferably made of flat bars, the wider sides being positioned so that the narrow edges will be positioned in the direction of the rotation of 65 the wheel, and it will be noted that the longer brace-rod are at the front of the wheel, where the strain will normally tend to extend the rods, and that the shorter bars are to the rear, where the strain tends to bend 70 the bars. The longer and shorter brace-rod alternate, and about midway between the rings E and F there is secured to the bars f a ring G, such ring having bearings g g for the outer ends of the double-crank rods h h. 75

The cranks formed on the inner and outer ends of the rods h h engage the horizontal flange of the collar or sleeve C and perforations in a movable ring H, so that when the sleeve is moved the ring H will be turned, and 80 as the ring is connected to the blades they will be moved with the ring.

The rings E and F, which constitute a part of the rigid frame of the wheel, have perforations or bearings for pins upon which the 85 blades I move. The pins i i' project from braces attached to the blades, the pins i' intersecting openings through the blades for the passage of the outer ring F.

The blades I carry hooks k, the outward 90 bent ends thereof being passed through openings in the ring H, so that when the ring is turned the blades will be moved in unison to place the wheel either in or out of operation.

A wind-wheel made in accord with my invention may be cheaply manufactured, the same will be thoroughly braced, and the angle of the blades may be quickly and easily changed. The conical casing will protect the sliding sleeve and the part of the shaft upon 100 which the sleeve slides from the weather.

Having thus set forth my invention, what I claim as new, and desire to secure by Letters Patent, is—

1. In a wind-wheel, a shaft having rigidly attached thereto a hub, a rearward-extending casing that is integral with the hub, a slide attached to the shaft within the casing and provided with a forwardly-extending flange, means for moving the slide on the 105 shaft, converging brace-rod carried by the hub, concentric rings attached to the brace-

rods, blades pivotally attached to the concentric rings and provided with hooks that project outward from the front edges of each of the blades, a ring carried by the hooks and 5 crank-bars connected to the movable ring carried by the blades and to the flange of the slide, for the purpose set forth.

2. In a wind-wheel, a shaft to which is rigidly secured a hub, a rearward-extending casing formed integral with the front portion of 10 the hub, a slide movable on the shaft within the casing, two series of brace-rods attached

to the hub and to the casing, concentric rings having bearings for the blades of the wheel carried by the outer ends of the brace-rods, a 15 ring attached to the outer brace-rods, crank-bars carried by said ring and the hub, a ring movable by the crank-bars such ring being connected to the blades of the wheel, substantially as shown.

ERICK P. BERGMAN.
